CARRYING CASE FOR A SLIDE PROJECTOR

David E. Hansen, Fairport, N.Y., assignor to Eastman
Kodak Company, Rochester, N.Y., a corporation of
New Jersey

Filed Apr. 9, 1965, Ser. No. 84,706

Term of patent 14 years

(Cl. D87—5)

FIG. 1

FIG. 3

FIG. 1 is a front perspective view of a carrying case for a slide projector showing my new design;

FIG. 2 is a rear perspective view thereof; and

FIG. 3 is a bottom plan view thereof.

I claim:

The ornamental design for a carrying case for a slide projector, as shown.
